ABSTRACT OF THE DISCLOSURE

The disclosure relates to a method of making a cover forming wooden lamellae for accordion doors and the like in sections corresponding to the length and height of the cover desired, in which a cover veneer of the desired length and height has its outer surface temporarily adhered to a plywood carrier of the same length and height, after which grooves that are too extend vertically of the cover veneer are formed in the cover veneer and the side of the panel carrier in spaced relation to define said cover veneer into alternating wide and narrow strips. A similar panel from which the cover in question is formed and having the same height and length with such grooves already formed in the front side of same has glued to its front face spaced textile strips that respectively overlie the pairs of closely spaced grooves that said grooves define, with further veneer strips being secured to such panel to fill in the space between the textile strips. The cover veneer is then glued to the cover forming panel across the said strips, with the grooves of each in alignment, and a blind veneer applied to the back side of the panel in question, after which the carrier panel is removed from the front side of the cover veneer to provide a panel from which a subsequent cover forming panel can be made. The back side of the cover forming panel in question is then formed with wedge shaped notches respectively aligned with and opening to the grooves formed on the front side of the panel to divide the panel in question into wide and narrow articulated sections. Covers so made are then applied to the opposite sides of a lazy tong type support to form an accordion door.

The invention relates to a method for the production of preferably multilayer foldable wooden lamellae, interconnected by articulated tapes whereby said tapes are covered by a covering veneer or the like, particularly for producing double shell folding doors (literally "accordion doors") and a folding door made in accordance with this method.

Folding doors comprise vertically arranged, stiff lamella parts interconnected by hinges, hinged tapes or articulated tapes, so that during the opening and closing of the door the lamella parts can be moved in an accordion-like manner.

The mass production of such wooden lamella connected with each other by articulation is extremely difficult because the double shell wooden folding doors known from prior art have lamellae of varying width, depending on the width of the room. The width of the lamellae thereby is always a fraction of the width of the room. Another disadvantage of the lamella made in line with the width of the room is that the frontal surfaces of the lamellae always diverge.

These disadvantages are avoided by the door according to the invention. According to the invention the lamellae are mass-produced at uniform width, whereby at different

2

room widths the lamellae in the door are placed at different angles to each other. Instead of the hitherto open anterior bisecting edges intermediate rods are glued in parallel to the operating direction of the door, which are in the same plane as the lamella surfaces.

As a rule the hinges, hinge tapes, or articulated tapes are placed on the inside of the wooden lamellae, resulting in the disadvantage that when the door is folded the frontal sides of the wooden lamellae become visible; this looks bad and makes it necessary to cover these frontal surfaces likewise with veneer.

In order to obtain a better optical overall impression, it is proposed to arrange the articulated tapes on the outside of the wooden lamellae and to cover them with

15 covering veneer. Thereby, the covering veneer is applied in strips to the individual wooden lamellae, so that a fugue remains between the covering veneers of two adjacent wooden lamellae which is flush with the fugue located behind the articulated tape between both wooden 20 lamella, whereby the mobility of the articulated tape is maintained as the door is moved.

It has been discovered that a sufficiently precise application of the covering veneer strips to the lamellae is practically unfeasible in mass production. It is impossible 25 to glue the cut veneer to the plywood with the precision of a fraction of an inch and to obtain that way a relatively wide and straight fugue. During the compression resulting from the gluing, the veneer may shift, making the desired precise execution of the fugues at the folding 30 points, by which the optical overall appearance and the operation of the door are influenced decisively, unattainable.

The aforementioned difficulties are to be obviated by the invention.

35 This problem has been solved by fastening a covering veneer on the surface side removably to a carrier plate, for example by gluing it on very lightly, by cutting into the cover veneer from the bottom at pre-determined intervals, first, longitudinally extending grooves, by cutting 40 into the surface of a lamella panel second grooves extending in accordance with the first grooves, by fastening to the surface of the lamella panel articulated tapes covering the second grooves, by placing the carrier plate with the cover veneer upon the lamella panel so that the 45 grooves match, and by gluing the cover veneer to the lamella panel, by cutting the lamella panel from the bottom side, preferably wedge-like as far as the second grooves and by removing the carrier panel from the covering veneer.

50 In the lamella panels the articulated tapes are applied only after cutting the grooves so that they cannot be damaged by the cutting tools. The cover veneer also is held firmly, after the application of the grooves, on the carrier plate until it is glued to the lamella panel. This 55 fully maintains the straight and uniform course of the grooves and of the grain of the wood over the entire front surface of the door without any shifting.

Another advantage of the method consists in that the panel first used as carrier panel can be used in the further course of the production as a pre-grooved lamella panel. This renders the method even more economical.

60 In order to obtain a smooth front surface as support surface for the cover veneer, it is possible to apply compensating veneer strips between the articulated strips or a milling may be applied to the plywood at a depth somewhat less than the thickness of the articulated tapes. The 65 fastening of the articulated tapes or strips, of the compensating veneer strips and the cover veneer on the lamella panels can be accomplished by gluing.

70 According to a further development of the invention a folding door with the lamella element made according to

the invention has been created, characterized in that intermittent bars are arranged between the lamella elements whose anterior surfaces are in one plane with the anterior edges of the basic bodies of the lamellae, in other words they are neither recessed nor projecting, and that the lamella elements and the intermediate bars are connected by articulated strips veneered below the cover veneer and forming one unit with the material of the basic lamella bodies and of the covering veneers.

In this embodiment the frontal sides of the lamella elements, located on the outside when the folding door is folded, are corners without separately projecting or recessed edges, because the frontal surfaces of the lamella elements are covered up by the intermediate bars. The lamella elements and the intermediate bars are covered by wooden veneers. Due to the fact that the front surfaces are close together and continuous in one plane that is the front surfaces of the basic lamella bodies and of the intermediate rods or bars the folding door then shows a decorative pattern of the wood graining, as it is neither discontinuous nor shifted. Only with this design is it possible to show a continuous wood pattern with the natural veneer design, the like of which no wooden folding door could show anywhere in the world. For the production it is favorable that the after-veneering of the longitudinal front edges of the lamella elements is eliminated. The articulated strips may be colored according to the color of the lamella elements. It is possible to use simple fabric or plastic tapes or such tapes reinforced by inserts as material for the articulated strips.

According to a further development of the invention the design may be such that the front ends located on the inside in folded position of said lamella elements are connected to carrier rods or bars fastened at the shearing skeleton, whereby two adjacent front ends each are inserted and fastened in a vertical slot in the carrier bar, so that with the door fully extended the front surfaces of the lamella elements of the intermediate bars form a smooth surface. This embodiment offers the advantage that with the telescoped or folded lamella position the outer surfaces of the intermediate rod adhere flatly to each other, so that even the telescoped or folded door package shows a smooth decorative wood pattern in one plane. This embodiment furthermore offers the advantage that even in the folded position of the door package hollow spaces remain between the individual lamella elements into which soundproofing inserts may be installed, for example,

Embodiments of the invention which show additional features of said invention are shown in the drawing.

FIGURE 1 shows in a sectional view a cover veneer fastened to a carrier plate 2 for the front sides of wooden lamellae 1 intended for a folding door,

FIGURE 2 shows in a sectional view a carrier plate 2 with cover veneer 1 according to FIGURE 1, with the grooves 2 cut in,

FIGURE 3 shows in a sectional view lamella panel 4 with cut-in grooves 5 and articulated tapes 6 glued on and overlapping the grooves 5, along with a compensating veneer 7,

FIGURE 4 shows in a sectional view the assembly of the cover veneer 1, the carrier plate 2 with the lamella panel 4, and

FIGURE 5 shows the lifting of the carrier panel 2 from the cover veneer 1 now solidly glued to the cover veneer 1 and the wedge-like cutting out 9 of the lamella panel 4 from the rear,

FIGURE 6 shows a perspective view of a door design where the wooden lamellae produced according to the method are used,

FIGURE 7 shows a longitudinal section thru the door according to FIGURE 6,

FIGURE 8 shows an enlarged partial presentation from FIGURE 7 and FIGURE 9 shows a lateral view of the presentation according to FIGURE 8.

The various steps of the method are shown consecu-

tively in FIGURES 1 to 5. All lamellae of a folding door or of a major folding door section, wooden lamellae in the embodiment, are worked out of a wide plywood panel only at the end of the production, said plywood plate being designated as lamella panel 4.

The cover veneer 1 with the proper dimensions to be applied to the anterior surface of the lamella panel is first glued removably with its later surface to the lower side of a stable carrier plate 2 (FIGURE 1). The grooves 3 later extending vertically are cut into the cover veneer 1 so fastened and into the carrier panel 2 from the bottom, whereby the cover veneer is separated into cover veneer strips which first remain at the carrier panel 2.

Grooves 5 are placed into the front side of the lamella panel 4. The grooves 5 are placed at the same intervals from each other as the grooves 3 of the carrier plate and also agree as to width with the grooves 3. The front surface of the lamella panel is then so glued with the articulated strips 6, textile strips for example, that the grooves 5 of the lamella panel are covered on both sides with sufficient overlapping. In order to obtain a smooth front surface compensating veneer strips 7 are glued between the articulated tapes on the lamella panel.

To a lamella panel so prepared the carrier plate 2 with the cover veneer 1 is now glued, whereby the grooves 3 and 5 are placed matching on each other and the cover veneer is glued firmly to the front surfaces of the articulated tapes 6 and the compensating veneer strips 7 (FIG. 4). At the same time the rear side of the lamella panel is glued to the blind veneer 8 during this operation.

Now that the cover veneer 1 is firmly glued to the lamella plate, the carrier plate 2 is removed from the covering veneer 1 (FIG. 5). The carrier panel 2 thereby released becomes during the further course of operation 35 the lamella panel. The lamella panel is cut wedge-like (9) from the bottom precisely below the grooves 3, so far that each wedge cut 9 reaches the superposed groove 3 from the bottom. The wedge-like design of the notches 9 establishes the mutual mobility of the lamella strips so that after the assembly into the folding door they can be displaced bellows-like and can pivot thereby.

FIGURES 6 to 9 show a double shell folding door with a shearing skeleton 11 located therein and placed in a vertical plane, said skeleton being covered on both sides with one outer shell each.

Each outer shell is connected via vertically extending carrier bars 12 made of wood with the shearing skeleton. Two basic wooden lamella bodies 4 are placed between two carrier bars each. Between the longitudinal front surfaces located on the outside in closing position of the basic lamella bodies one intermediate wooden bar 13 is arranged extending parallel to the anterior edges of the lamellae. Two basic lamella bodies 4 form one lamella element with the intermediate bar. Near their outer and inner longitudinal edges the lamella bodies are coated 55 on their front side with flexible articulated tapes 6. On the outside the articulated tapes are guided over the intermediate bars 13 from one basic body to another one and glued on. In the inner areas the articulated tapes connect the basic bodies to the carrier bars 12. They have on the outside surfaces 14 slanting toward each other. The front edge formed by the slanted surfaces is slit open. The laterally projecting articulated tapes 6 of the adjacent lamella elements are placed into said slot 15 and connected to the carrier rod by gluing, pasting or nailing. 60 10 identifies a wire pin.

A compensating veneer 7 is pasted between the articulated tapes on the front surface of each basic body and the smooth front surfaces of the basic bodies so formed and the intermediate bars covered with the articulated tapes are covered by covering veneers. The adjacent longitudinal surfaces of the basic bodies and of the intermediate rods 13 are undercut. The inner surfaces of the basic bodies and the intermediate bars are coated with 65 veneers likewise.

As the folding door is folded together smooth corners form on the outer ends of the lamella elements, whose outer edges are formed by articulated tapes, resulting in a near appearance.

We claim:

1. A method for the manufacture of preferably multi-layer foldable wooden lamellae, interconnected by articulated tapes, said articulated tapes being covered by a covering veneer or the like, particularly for the production of double shell folding doors, characterized by the fact

that a covering veneer (1) is fastened on the surface side to a carrier panel (2) removably, that first longitudinally extending grooves (3) are cut from the bottom into the covering veneer (1) and the carrier panel (2) at predetermined intervals, that second grooves (2) extending in accordance with the first grooves are cut into the surface of a lamella panel (4), that articulated tapes (6) covering the second grooves are fastened to the surface of the lamella panel, that the carrier plate (2) is placed with the covering veneer (1) on the lamella panel (4) so that the grooves match and the covering veneer (1) is connected to the lamella panel, that the lamella panel is cut, preferably wedge-like from the bottom side in to the second grooves (5) and that the carrier plate (2) is removed from the covering veneer.

2. A method according to claim 1, whereby the carrier panel (2) is used in the subsequent operation as lamella panel (4).

3. A method according to claim 1 whereby the removable fastening of the cover panel veneer (1) to the carrier panel (2) is accomplished by slight gluing or pasting.

5 4. A method according to claim 1, whereby compensating strips (7) are fastened on the lamella panel (4) between the articulated strips (6).

10 5. A method according to claim 3, whereby the articulated tapes (6), the compensating strips (7) and the cover veneer (1) are fastened to the lamella panel (4) by gluing.

15 6. A method according to one of the preceding claims, whereby the lamella panel (4) is made from plywood covered on the back side by a blind veneer (8).
